(57) **CLAIM**

We claim the ornamental design for a holding device for video recorder, as shown and described.

DESCRIPTION

FIG. 1 is a front perspective view of a holding device for video recorder;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top view thereof; and,

FIG. 8 is a bottom view thereof.

Dark broken lines depict the bounds of the Claim. Light broken lines depict portions of the holding device for video recorder that form no part of the claimed design.
